3 SHEETS—SHEET 3.

UNITED STATES PATENT OFFICE.

EDWARD MANNING, OF RUTLAND, VERMONT, ASSIGNOR TO MANNING MANUFACTURING COMPANY, OF RUTLAND, VERMONT, A CORPORATION OF VERMONT.

CAN-WASHING MACHINE.

1,137,345.

Specification of Letters Patent. Patented Apr. 27, 1915.

Application filed November 19, 1914. Serial No. 872,972.

To all whom it may concern:

Be it known that I, EDWARD MANNING, a citizen of the United States of America, residing at Rutland, in the county of Rutland 5 and State of Vermont, have invented certain new and useful Improvements in Can-Washing Machines, of which the following is a specification, reference being had therein to the accompanying drawing.

10 This invention relates to certain new and useful improvements in can washing machines for washing cylindrical cans of all kinds; the object being to provide a machine which is exceedingly simple and cheap in 15 construction and one in which a tank is employed in which the can to be washed is placed and supported upon suitably arranged brushes so constructed that the inside and outside of the can can be quickly 20 washed; said brushes being controlled independently in order to enable the operator to cause the can to rotate with the inside set of brushes or to be held stationary by the 25 outside set of brushes so that the inner and outer surface of the can can be thoroughly washed.

Another object of my invention is to provide a can washing machine with an expandible brush to receive the can and with movable 30 brushes for washing the outside of the can together with means for operating said brushes so as to cause the can to be rotated with the expansible brush or to be held stationary by the movable brushes.

35 Other and further objects and advantages of the invention will be hereinafter set forth and the novel features thereof defined by the appended claims.

In the drawings Figure 1, is a perspective 40 of my improved can washing machine; Fig. 2, is a longitudinal horizontal section showing the expandible head in contracted position, the can being shown in dotted lines in 45 position on the brushes; Fig. 3, is a detail perspective of the rack members for operating the segmental gears formed on the ends of the brush-supporting arms; Fig. 4, is a 50 transverse section showing a can in position upon the expandible head, the outside brushes being in their normal positions; Fig. 5, is an elevation of the bottom brush and operating means, showing the same in 55 engagement with the bottom of a can; Fig. 6, is a detail perspective of one set of brushes carried by the expandible head; Fig. 7, is

a detail enlarged elevation of the expandible head.

Like numerals of reference refer to like parts in the several figures of the drawings.

In carrying out my invention, I employ a 60 tank 1 which is mounted upon legs 2 and is formed at one end of a greater height, having a hinged cover 3 for closing the same which is provided with a centrally arranged opening for the purpose hereinafter fully 65 described.

Extending out from the enlarged end of the tank is a bracket 4 provided with a bearing 5 in longitudinal alinement with a bearing 6 secured upon the end of the tank and 70 mounted within said bearings is a shaft 7 which is provided with tight and loose pulleys 8 and 9 over which passes a drive belt 10, the shipper means for said belt not being shown, it, of course, being understood that 75 any well-known form of shipper can be employed for shifting the belt from the tight to the loose pulley or vice versa.

The driven shaft 7 extends into the enlarged end of the tank and fixed thereon, is 80 a head 11 having spaced oppositely disposed lugs on the top and bottom faces of which are mounted arms 12 and 13 upon pivots 14 and 15 which extend through said lugs and plates 16 secured in position upon the top 85 and bottom of the head by bolts 17. The plates are provided with centrally arranged longitudinally disposed enlarged groove portions 18 in which are mounted racks 19 and 20 which are adapted to coöperate with 90 the segmental gears 21 and 22 formed respectively upon the arms 12 and 13, whereby said arms will be rocked upon their pivots as the racks are reciprocated so as to move the arms outwardly and inwardly for 95 the purpose hereinafter fully described. The free ends of the arms 12 and 13 are pivotally connected to brushes 23 and 24 as clearly shown in Fig. 2; the brush 24 being provided with an end portion 25 adapted to 100 engage the inside bottom of the can when the can is placed in position thereon.

The rack bars 19 and 20 are carried by 105 guide rods 29 adjustably mounted in bearings 30 formed on the collar 31 slidably mounted upon the driven shaft 7; said guide rods passing through guide eyes 32 of a sleeve 33 fixed on said driven shaft as clearly shown in Fig. 3. Surrounding the driven shaft 7 between the sleeve 33 and the 110

collar 31 is a coil spring 34 for returning the racks to their initial positions after they have been moved against the tension of said spring, as will be later described. The 5 sleeve 33 is provided with oppositely disposed lugs 35 on which are mounted links 36 which have their ends connected respectively to the brushes 23 and 24, as clearly shown, so that when the brushes are moved 10 outwardly, the inner ends thereof will be supported by said links.

In order to provide means for reciprocating the rack bars 19 and 20 to cause the 15 brushes carried by the head to be expanded, a yoke 37 is loosely mounted upon the driven shaft 7 the end 38 thereof, being arranged within the tank and adapted to engage the sleeve 31 so as to shift the sleeve upon the driven shaft which in turn, will 20 push the rack bars through the medium of the rods so as to cause the arms carrying the brushes to be thrown outwardly. A suitable bracket 39 is mounted on the tank and carries a lever 40 which is connected to the 25 yoke 37 and is supported at its free end by a guide bracket 41 as clearly shown in Fig. 1. The free end of the lever 40 is connected to a bell crank 42 mounted upon the side of the tank by a rod 43 the opposite arm of 30 said bell crank being connected to a treadle 44 mounted upon a stud projecting from one of the legs of the tank by a rod 45 and it will be seen that when the treadle is pushed 35 downwardly by the operator exerting a pressure thereon with his foot, the crank will be rocked and through the medium of the connecting rod and lever, the yoke will be shifted upon the driven shaft.

In order to return the treadle to its normal 40 position, I arrange a bar 46 on the outside of the tank having a hooked end to which is connected one end of a coil spring 47 the opposite end being connected to the bell crank 42 as clearly shown in Fig. 1.

45 It will be seen from the construction so far described, that I have provided an expandible head to receive a can to be washed having brushes which are so mounted therein that they can be thrown into contact with the inner surface of the can so as to thoroughly wash the same, or thrown into engagement with the inner surface of the can under such a pressure that the can will be rotated therewith.

50 In order to provide means for washing the outer faces of the can, I arrange within the tank, brackets 48 and 49 in which are mounted parallel curved levers 50 and 51 the free ends of the levers 50 being connected 55 together by a brush 52 and the free ends of the levers 51 being connected together by a brush 53. The levers are loosely connected as shown at 54 so as to rock together whereby the two brushes will be thrown simultaneously into engagement with the outer

surface of the can. The levers 50 have extensions 55 to which are pivotally connected operating rods 56 which are mounted in suitable bearings 57 adjacent their upper ends. The free ends of said rods extend 70 through openings 58 formed in the cover 3 and are surrounded by coil springs 59 between the inner face of the cover and the bearings 57, said springs having their lower ends resting upon the bearings 57 and their upper ends connected to said operating rods so as to normally hold the operating rods in raised position, which in turn will hold the brushes out of contact with the can. It will be seen by this construction, that the outside brushes are normally out of the path of the can when being inserted or removed. 80

The tank is provided with bearings 60 in which are pivotally mounted the arms of a frame 61 which carries a brush 62 adapted 85 to pass down through the opening of the cover 3, said frame being normally held in a raised position by a coil spring 64 as clearly shown in Figs. 1 and 4. The arms of the frame 61 are arranged in vertical alignment with the projecting ends of the operating rods 56 so that when the frame 61 which is provided with an operating handle 63 is forced downwardly by exerting a pressure upon said handle, the arms will engage 95 the ends of the operating rods 56 so as to rock the levers which in turn will move the brushes into engagement with the outer face of the can, it of course, being understood that the brush 62 is simultaneously brought 100 into engagement with the can.

In order to provide means for washing the bottom of the can, I arrange within the tank a suitable rock shaft 65 which has an arm 66 connected thereto carrying a brush 105 67 which is preferably shaped so as to conform to the outer surface of the bottom of the can, said shaft 65 being provided with a crank 68 to which is connected a link 69 said link being connected at its free end to an angular lever 70 mounted upon a pivot 71 arranged in the side of the tank and guided by a suitable guide member 72 the upper end of said lever being provided with a handle portion projecting slightly above 110 the edge of the tank in such a position that the same can be readily grasped by the operator so as to shift the lever which in turn, through the link and crank connection, will throw the brush 67 into and out of engagement with the can. The tank 1 is of sufficient length to allow a can to be readily inserted or removed therefrom and it will be seen that by placing the can in a horizontal position within the tank and forcing the 115 same onto the expandible head, the same will be supported by said head and by operating the treadle 44 the head can be expanded so as to exert a pressure on the inner surface of the can to such an extent that the 120

130

- can will be carried with the head and by pressing downwardly on the handle 63 and drawing the lever 70 toward the operator, the brushes 52, 53, 62 and 67 will be simultaneously thrown into engagement with the outer surface of the can so as to thoroughly clean the outer surface of the can as the can is rotated. By releasing the pressure on the treadle 44 and exerting a greater pressure upon the handle 63 and lever 70, the can will be held stationary and the brushes carried by the expansible head will rotate therein so as to thoroughly clean the inside of the can. After the can has been thoroughly washed in this manner, the same is removed from the expansible head and placed upon a rinsing sterilizing device 73 arranged at the opposite end of the tank 1 as clearly shown in Fig. 1.
- 20 From the foregoing description, it will be seen that I have provided a can washing machine in which provision is made for exerting pressure upon the respective brushes so as to hold the can when rotating, at the operator's will, thereby allowing one set of brushes to clean either the outer or inner surface as the case may be, while the can is held stationary by the other set of brushes. It will also be seen that the brushes are so constructed that they conform to the conformation of the well-known form of cans now in use so as to thoroughly clean all of the surfaces thereof.

In the operation of my improved construction of can washer, the tank is partly filled with water so that the can will be partly submerged when being washed and while in the drawings, I have failed to show any inlets and outlets for the tank it is, of course, understood that suitable ports can be provided for filling and emptying the tank.

I claim:

1. In a can washing machine, the combination with a tank, of a driven shaft, an expansible head carried by said shaft, a pair of brushes mounted within the bottom of the tank, a hinged frame mounted above said tank, a brush carried by said hinged frame, and means operated by the downward movement of said hinged frame for throwing said pair of brushes toward each other.
2. In a can washing machine, the combination with a vat, of a revolute shaft mounted in said vat, a head carried by said shaft, expansible brushes carried by said head, brushes arranged parallel to one another within said vat, levers upon which said brushes are mounted, a connection between said levers, and means for operating one pair of levers so as to simultaneously move said brushes toward each other.
3. In a can washing machine, the combination with a tank, of brackets mounted in

the bottom of said tank, levers mounted in said brackets and extending parallel to each other, a connection between said levers, brushes connecting the respective pair of said levers, spring-actuated rods connected 70 to one pair of levers, and a pivoted frame adapted to engage said spring-actuated rods for rocking said levers upon their pivots.

4. In a can washing machine, the combination with a tank, of a revolute shaft 75 mounted in said tank, a head fixed on said shaft, levers pivotally mounted in said head provided with gear portions, racks coöperating with said gears, brushes carried by said levers, and means for operating said 80 racks so as to rock said levers.

5. In a can washing machine, the combination with a tank, of a revolute shaft mounted in said tank, a head carried by said shaft, expansible brushes carried by said 85 head, means for expanding said brushes, a pair of brushes mounted within said tank, means for moving said brushes toward each other, and a top brush carried by a frame having a connection with said pair of 90 brushes for operating said brushes.

6. A can washing machine, having a revolute shaft provided with a head, expansible brushes carried by said head, outside brushes arranged within the tank, 95 means for moving said brushes toward each other, and a top brush carried by a frame having a connection with the bottom brushes for simultaneously moving said bottom and top brushes toward each other.

7. A can washing machine, comprising a tank having inside and outside brushes for washing a can, said inside brushes being carried by an expansible head, the outside brushes being capable of moving toward the 105 inside brushes, means for expanding the inside brushes, and means for simultaneously moving said outside brushes toward each other.

8. A can washing machine, comprising a 110 tank, a pair of pivotally mounted brushes mounted in said tank, a connection between said brushes, an expansible head revolubly mounted in said tank, a movable top brush, and a connection between said movable top brush and one of said pivotally mounted brushes.

9. An expansible head for can washing machines, comprising a series of pivotally mounted links provided with segmental gear 120 portions, spring-returned racks coöperating with said gear portions, and means for moving said racks against the tension of said spring.

10. In a can washing machine, the combination with a revolute shaft, of a head fixed on said shaft, levers pivotally mounted in said head provided with gear portions, brushes carried by said levers, a sleeve mounted upon said shaft, links connecting 125 130

said sleeve to said brushes, rods having a sliding connection with said sleeve, racks carried by said rods coöperating with the gears of said levers, a collar slidably mounted upon said shaft, an adjustable connection between said collar and rods, a spring surrounding said shaft between said collar and sleeve, and means for shifting said collar upon said shaft.

11. In a can washing machine, the combination with a tank having an enlarged portion at one end, a hinged cover for said enlarged portion provided with an opening, a pivoted frame, extending above said cover, a brush carried by said frame adapted to pass through said opening, vertically disposed rods arranged within said tank extending through openings in said cover in vertical alinement with said frame, springs surrounding said rods for exerting an upward pressure thereon, levers pivotally mounted within said tank having an adjustable connection with said rods, a brush connecting the free ends of said levers, a second set of levers pivotally mounted within said tank, a brush connecting the free ends of said second set of levers, a sliding connection between the first set and second set of levers, and means for holding said frame out of contact with said rods.

12. In a can washing machine, the combination with a tank having a revolute shaft mounted therein, of a head carried by said shaft, expandible brushes carried by said head, springs for holding said brushes in contracted position, means for expanding said brushes, and a second set of brushes arranged within said tank having means for simultaneously moving said second set of brushes toward the expandible brushes.

13. A can washing machine having a pair of pivotally mounted can supporting brushes mounted therein, means for moving said brushes simultaneously into engagement with the can, a top brush, and a connection between said top brush and pivotally mounted brushes for operating the can-supporting brushes simultaneously.

14. In a can washing machine, the combination with a tank, of a pair of pivotally mounted can-supporting brushes arranged therein, a movable top brush, means for shifting the can-supporting brushes toward each other, and means operated by the movement of the top brush for operating said brush-shifting means.

15. In a can washing machine, the combination with a tank, of an expandible brush mounted therein, treadle mechanism for expanding said brush, movable can-supporting brushes mounted within said tank, a pivoted top brush, and mechanism operated by the movement of the top brush for moving said can-supporting brushes toward each other.

16. In a can washing machine, the combi-

nation with a driven shaft, of an expandible brush carried by said shaft, treadle-operated mechanism for expanding said brush, can-supporting brushes mounted within said tank and capable of moving independently of said expandible brush, a bottom brush, a lever for operating said bottom brush, a top brush for engaging said can, and mechanism operated by the movement of the top brush for moving said can-supporting brushes simultaneously toward each other.

17. In a can washing machine, the combination with a tank, of a spring-supported pivotally mounted frame, a brush carried by said frame, spring-actuated rods arranged in the path of travel of said frame, can-supporting brushes mounted within said tank having a connection with said spring-actuated rods, and a handle carried by said frame.

18. In a can washing machine, the combination with curved levers having a sliding connection, of brushes carried by said levers, rods connected to one pair of levers, and a movable frame mounted above the free ends of said rods and adapted to engage said rods on the downward movement thereof, said movable frame carrying a top brush.

19. In a can washing machine, the combination with a tank, of a pair of movably mounted brushes for supporting a can therein, a connection between said movably mounted brushes, a revolute expandible brush to receive said can, means for operating said expandible brush, and means for operating one of said movably mounted can-supporting brushes, for causing said can to be held stationary in respect to the revolute brush.

20. In a can washing machine, the combination with a pair of movably mounted can-supporting brushes, vertical rods for operating said brushes, a brush frame pivotally mounted above said tank adapted to coöperate with said rods, a brush carried by said brush frame, and a handle extending from said brush frame for exerting a downward pressure thereon for simultaneously operating said brushes.

21. In a can washing machine, the combination with a tank having a driven shaft mounted therein, a head carried by said shaft, levers pivotally mounted in said head provided with rack portions, brushes carried by said levers, a sleeve fixed on said shaft provided with guides, rods mounted in said guides, racks carried by said rods co-operating with said gears, a lever loosely mounted upon said shaft, an adjustable connection between said collar and rods, a yoke mounted upon said shaft, a lever having a connection with said yoke, and a treadle mechanism for operating said lever.

22. In a can washing machine, the combination of can-supporting brushes, means for

moving said brushes toward and away from each other, a top brush, an expansible head having spring-retumed brushes, and means operated by a treadle for expanding said 5 brushes.

23. An expansible brush for a can washing machine, comprising a rotating shaft having a head mounted thereon, arms pivotally mounted in said head provided with 10 segmental gears, brushes carried by the free ends of said arms, racks mounted in said head coöperating with said gears, and means for moving said racks.

24. An expansible brush for can washing machines, comprising a revoluble shaft having a head fixed thereon, arms pivotally mounted in said head provided with segmental gears, brushes carried by the free ends of said arms, racks slidably mounted in 20 said head coöperating with said gears, rods connected to said racks, a spring-actuated

collar slidably mounted upon said shaft adjustably connected to said racks, and a sleeve fixed on said shaft provided with guide eyes to receive said rods.

25. An expansible brush for a can washing machine, comprising a revolubly mounted shaft having a head fixed at one end, arms pivotally mounted in said head provided with segmental gears, brushes carried by the free ends of said arms, spring-actuated racks mounted in said head coöperating with said gears, and means for moving said racks against the tension of said spring to expand said brushes.

25 In testimony whereof I hereunto affix my signature in the presence of two witnesses.

EDWARD MANNING.
